[57] **CLAIM**

The ornamental design for a paving stone, as shown and described.

DESCRIPTION

FIG. 1 is a perspective view of a paving stone showing my new design;

FIG. 2 is a bottom plan view thereof;

FIG. 3 is a side elevation view thereof;

FIG. 4 is a perspective view of a second embodiment of the paving stone;

FIG. 5 is a perspective view of a third embodiment of the paving stone; and,

FIG. 6 is a side elevation view of the second and third embodiment thereof.

The sides of the three embodiments of the paving stone not shown in the drawings are understood to be flat and unornamented and the bottom of the second and third embodiments of the paving stone is flat and ornamental.
